UNITED STATES PATENT OFFICE

GEORGE F. GALLAGHER, OF CHICAGO, ILLINOIS, ASSIGNOR TO KREM-KO COMPANY, OF CHICAGO, ILLINOIS, A CORPORATION OF ILLINOIS

DESIGN FOR A BOTTLE OR SIMILAR ARTICLE

Application filed August 19, 1929. Serial No. 32,448. Term of patent 14 years.

To all whom it may concern:

Be it known that I, GEORGE F. GALLAGHER, a citizen of the United States, residing at Chicago, in the county of Cook and State of Illinois, have invented a new, original, and ornamental Design for a Bottle or Similar Article, of which the following is a specification, reference being had to the accompanying drawings, forming part thereof.

The figure is a front elevational view of a bottle showing my new design.

I claim:

The ornamental design for a bottle or similar article, substantially as shown.

GEO. F. GALLAGHER.
